WRINGER

Henry L. Morin, Holyoke, Mass.

Application July 26, 1933, Serial No. 682,217

12 Claims.

(CL. 68—32)

This invention relates to improvements in wringers for drying washed clothes. One object of the invention is to provide a wringer having improved means for securing the desired tension between the pressure rolls. Another object is to combine a device for releasing certain parts for a dismantling operation with the tension controlling means, so that a single handle only will be required. Another object is to improve the safety features of the wringer, both with regard to its simplicity and reliability in operation and to the freedom from any possibility of the operator receiving an accidental electric shock. Another object is to improve the manner of feeding clothes to and from the pressure rolls. Another object is to improve the mechanical construction of wringers of this general type in the matters of simplicity and economy of manufacture. Additional objects will appear from the following description and claims.

Referring to the drawings:

Fig. 1 is a side elevation of a wringer constructed in accordance with the invention;

Fig. 2 is a top plan view thereof, with certain parts broken away;

Fig. 3 is a detail section, on a scale larger than Figs. 1 and 2, taken on line 3—3 of Fig. 4;

Fig. 4 is a top view, of the parts shown in Fig. 3, but with the top roll and its bearings removed;

Fig. 5 is a view, with certain parts broken away, of the opposite side of the device from that shown in Fig. 3;

Fig. 6 is a fragmentary sectional view of one side of the wringer, substantially on line 6—6 of Fig. 3;

Fig. 7 is a perspective view of the main frame;

Fig. 8 is a fragmentary central section through the device;

Fig. 9 is a detail thereof with the parts in different positions;

Fig. 10 is an end view thereof with certain parts broken away;

Fig. 11 is a central transverse section through the device;

Fig. 12 is a fragmentary central transverse section showing a modification;

Fig. 13 is a detail of the modification of Fig. 12;

Fig. 14 is a detail of a preferred form of feeding belt;

Fig. 15 is a fragmentary longitudinal section, showing a modified form of safety device; and

Fig. 16 is an end view of the mechanism of Fig. 15, showing a modification.

The wringer is carried in a main frame 20 of general U-form, preferably of pressed metal as

shown in Fig. 7. This frame has channel shaped sides 21 merging into a bottom portion 22 that is in general trough shape. Wings 23 extend outwardly from the channel shaped sides and join the bottom 22. Adjacent the upper inner edges of the channels 21 the metal is bent inwardly as at 24 to form guide ribs the function of which will appear below. One channel 21 has fixed to it adjacent its upper edge as by rivets 25 (Fig. 8) a pair of clips 26 having slots 27 exposed beyond the upper edge of the channel. The other channel has its metal struck up inwardly to form a pair of holes 28.

The two wringer rolls 30 and 31 are provided respectively with end shafts 32 and 33. In the form first to be described one end of the shaft 33 is provided with a pin 34 serving for driving engagement with any standard wringer mechanism. The two wringer rolls are carried at each end in a sub-frame 35 adapted to lie within the flanges 24 as shown in Fig. 4 and having struck up lips 36 passing outside these flanges so as to provide a sliding contact. By this means the sub-frame can be drawn vertically out of the channels 21 and yet when in place will be held firmly in position. The sub-frames are provided with holes 37 and struck up ribs 38 to engage with sliding action bearing blocks 39 and 40 which serve respectively for the upper and lower shafts 32 and 33. The upper shaft has a single bearing block 30 on its upper surface and the shaft 33 has a single bearing block on its lower surface. This is in all cases sufficient as the rolls are always pressed towards each other. The lower bearing block 40 on each side is held in place by a bulging portion 41 of the sub-frame. On one side of the wringer the two rolls are geared together by spur gears 42 and 43 (Fig. 5) of the usual type, suitably secured to the roll shafts. On the other side of the machine is mounted the safety control mechanism which will be described below.

Before going into the details of the safety control mechanism the devices for carrying the clothes through the wringer and the control actuating devices will be considered. Each of the wing portions 23 of the main frame is provided with a stud 45 having an enlarged head 46. On each of these studs is carried a plate 47 (Fig. 11) having formed in it a keyhole shaped slot 48 having its larger end placed toward the central portion of the wringer. If the plate is moved outwardly so as to bring the enlarged portion of the hole 48 into registration with the stud 45, the plate can be removed easily, otherwise, it is anchored firmly in place. The lower portion of the

plate has a downwardly extending lug 49 adapted to rest upon the bottom 22 of the frame as shown in Fig. 11. Plates 47 are formed with end studs, or with a central shaft 50 upon which is mounted 5 rolls 51 preferably of wood. Around the two rolls 51 and around the lower wringer roll 31 is stretched a belt 52 preferably of rubber having perforations 53 to permit drainage of water. Slippage of the belt as the clothes pass between 10 the wringer rolls is prevented by the positive driving action of gears 42 and 43, but it will be understood that any suitable means for driving the belt may be employed. The outer surface of the belt is preferably corrugated as at 54. It will be understood that the clothes to be dried are placed upon the belt 52 and are carried by it between the pressure rolls, the water squeezed out of the clothes passing freely through the holes 53 and being received upon the inwardly sloping bottom 22 of the main frame. At the center of this frame bottom is a hole 56 shown in Figs. 7 and 11. The hole is conveniently formed by striking outwardly the metal of the frame bottom so as to form 15 lugs 57. A drain board 59 having upwardly inclined sides 60 is pivotally connected to lugs 57 by bolts 58, and may be tipped in either direction to deliver the water as may be desired. Due to 20 the pivotal mounting of the plates 47 the wooden rolls 51 may be raised as shown in dotted lines in Fig. 11, permitting the bottom of the wringer frame to be wiped dry. As clearly shown in Fig. 1 plates 47 are pivoted above the center line of the 25 rolls so that when in normal operating position the plates 47 tilt downwardly and this tilted arrangement serves to lock the rolls in operative position. This tilting is also useful in shortening the effective length of the belt and thereby relieves the wood rolls of tension so that the plates 30 may be slipped clear of the studs 45. Mounted above the belt 52 and pivoted to the frame as at 65 are a pair of oppositely extending guard plates 66. These plates can be raised sufficiently to 35 permit the passage of clothes underneath them but cannot be raised enough to allow the operator's hand to reach the wringer rolls without tripping the safety device which will now be described.

50 At the upper portion of the guides 38 which carry the upper bearing block 39 a pair of exposed tongues 70 are struck out as shown in Figs. 3, 4, and 6. These lugs form pivots for a plate 71 having portions 72 turned at right angles and 40 provided with pivot holes 73. The right angled portions 72 are also provided with suitable portions 74 adapted to rest against the wall of the sub-frame 35 and thereby prevent inward movement of the plate 71 beyond the desired point. At 45 one side the plate has an extending portion 75 bearing a hook 76 best shown in Fig. 6. This hook is adapted to engage a lug 77 formed upon a casing 78 pivoted to the sub-frame at 79 and adapted to contain a mercury switch of the well known 50 commercial type. These switches comprise a sealed glass tube generally evacuated except for a small quantity of mercury. With the tube tipped into the dotted line position of Fig. 3 the mercury bridges a pair of electrical contacts 55 sealed into the glass tube. An electrical current can be maintained in the circuit indicated by the wires 80. If the plate 71 has its lower end 60 swung outwardly so that it releases the lug 77, the weight of the casing 78 assisted if desired by a spring 81 will cause the casing to drop to a

lower limit determined by its end portion striking against the wall of the channel 21 as shown in full lines in Fig. 3. In this position the casing is tilted downwardly in the opposite direction so that the mercury runs away from the electrical 5 contact and breaks the circuit. The driving motor of the wringer is included in this circuit so that releasing the casing 78 will cause immediate stoppage of the motor.

In order to release the casing 78 by swinging 10 plate 71 outwardly while permitting a limited upward movement of the guards 66, these guards have fixed to their inner ends arms 85 which as shown in Figs. 4 and 6 are curved in form. For a limited upward movement of the guards 66 15 these arms do not contact the plate. If, however the guards are moved upwardly a distance corresponding to that produced by the insertion of the operator's hand beneath them the arms contact a cam-like flange 86 formed on the adjacent edge 20 of the plate 71 and move the latter outwardly so that the lug 77 will be released.

In order to reset the safety device and thus restart the motor after the cause of its stopping has been corrected, a finger piece 87 is fitted to 25 slide in a slot 88 (Fig. 7) in one side of one of the channels 21. Attached to this finger piece is a wire link 89 connected to the free end of the casing 78. By raising the finger piece the casing 78 will be raised also, being held in raised position 30 as soon as the lug 77 passes the hook 76. The lower position of casing 78 is also determined by the engagement of piece 87 with the bottom of slot 88. It will be observed that a guard 66 is provided on each side of the machine so that the 35 wringer may be operated in either direction and that these guards operate independently of each other upon the mechanism. This double structure when considered in relation to the perforated belt 52 has an additional advantage that the dry- 40 clothes will be conveyed away from the rolls to a place more convenient for their disposition than if the belt terminated at the lower pressure roll on one side. A mechanism for holding the upper pressure roll 30 in contact with the lower 45 roll 31 has also been provided. This mechanism, being shown best in Figs. 8, 9, and 10, is mounted within a cap 95 having at one side struck up lugs 96 adapted to fit into the holes 28 in the main frame. At the other side the cap is provided 50 with a bracket 97 loosely supporting a hook 98. Normally the lower end of this hook is forced by a spring 99 into engagement with the holes 27 in the members 26. The spring is mounted upon a shaft 100 pivoted in the cap at one end and at a 55 U-shaped bridge piece 101 suitably secured in the center of the cap. The spring may be held compressed upon the shaft by a washer 102 and a cotter pin 103. The shaft is provided with a handle 104, the hub portion of which extends inside of 60 the cap and bears a cam piece 105. When the handle is suitably rotated as shown in Fig. 9 the cam portion will engage the hook 98 and push it out of engagement with the holes 27 so that the 65 cap is free to be removed from the frame.

Bridging the upper bearings 39 is bow spring 110 having at its central portion a pair of clips 111 provided with vertical slots 112 to embrace the shaft 100. On the shaft 100 in the center of the bridge piece 101 is keyed a cam 113 having a 70 series of substantially flat surfaces 114 to 118 inclusive adapted to bear upon the upper surface of the spring 110. The cam and the spring are so designed that when the surface 118 is brought over the spring the spring is completely released from 75

compression. In this same position the cam 105 moves the hook 98 out of engagement with the hole 27 so that by a single motion of the handle the rolls can be relieved of compression and the cap freed by removal from the frame. The other surfaces of the cam 113 serve to give varying degrees of compression to the spring. The ends of the spring 110 engage spacer members 119 resting on bearings 39. It is preferable although not necessary that a scraper or doctor be provided upon the upper roll. In the drawings a rubber scraper 120 has been shown held by clips 121 to the members 119. This scraper if used will prevent the clothes passing around the upper roll, a condition which is difficult to remedy due to the thoroughly enclosed condition of the pressure rolls. This enclosed condition is of course desirable for purposes of safety as it is practically impossible to get the hands or any large object between the rolls.

In Fig. 12 a modification has been shown in which the guard plates 66 have been replaced by rolls 125, preferably knurled to assist in gripping the clothes, mounted upon plates 126 pivoting in the frame as in the case of the original guard plates. These rolls are driven upon the upper roll 30 by a small V-belt 127 passing around the rolls and around small guide pulleys 128. This form of the invention has the advantage that it assists in feeding the clothes to a point between the wringer rolls. Another modification has been shown in Figs. 15 and 16 in order to illustrate the adaptability of the wringer to various control mechanism. In this case the casing 78 and its enclosed mercury switch has been replaced by a mechanical clutch mechanism. For this purpose the plate 71 is removed and a plate 130 put upon the machine in its place, being pivoted at its lower end 130' to the sub-frame. The driving shaft 33 of the lower roll is cut so that it does not directly engage the driving mechanism but carries one member 131 of a two part dog clutch. The other member 132 of this clutch is secured to a driving shaft 133 and is pressed against the member 131 by a spring 134 acting against a collar 135 upon a shaft 133. The plate 130 is provided with a cam-like portion 136 positioned to engage the outer portion of the clutch member 132. The arms 35 previously described, are adapted when swung downwardly to engage cam-like portions 137 on the plate 130 so that as the guard plates 66 are raised the plate 130 will be swung outwardly and the clutch 131, 132 will be moved into inactive position. It will be obvious that other changes in detail structure may be made to suit individual installations without departing from the invention as set forth in the appended claims.

I claim:

1. In a wringer mechanism, a frame, a pair of wringer rolls mounted in said frame, the upper roll being removable, a cap member, means for releasably locking the cap member to said frame, a spring means urging the upper roll toward the lower roll, a shaft, a cam on said shaft and positioned between the cap member and spring to control the pressure exerted on the upper roll by said spring means and a second cam on said shaft for releasing the cap member locking means, the relative position of said cams being such that said second cam operates when the spring pressure is substantially relieved by the first cam.

2. In a wringer mechanism a frame including side members, a pair of wringer rolls mounted between the side members, the bearings of the upper roll being slidably mounted in the side mem-

bers to permit removal of the upper roll from the frame and movement of said upper roll toward the lower roll, a cap member having one end pivotally engaging one side member, the other end being provided with a catch releasably engaging the opposite side member, a spring member bridging the upper roll with its ends acting against the bearings of the upper roll, a rock shaft mounted in said cap member, a cam member eccentrically mounted on said shaft and engaging said spring to control the pressure exerted by the spring on the bearings of the upper roll, and a second cam on said shaft positioned to release said catch when the first named cam is positioned to relieve the pressure of said spring on the bearings of the upper roll.

3. In a wringer mechanism including a pair of wringer rolls, a belt having its upper run passing between said rolls, an apron positioned beneath the belt and projecting sidewise from the wringer rolls, a pulley roll, about which the belt passes, movably mounted on the outer end portion of the apron, to permit upward movement of the pulley and belt with respect to the apron to afford access to the latter.

4. In a wringer mechanism including a pair of wringer rolls, a belt for feeding clothes to and from the wringer rolls, the upper run of said belt passing between said rolls, an apron projecting from each side of the wringer rolls, pulley rolls positioned on opposite sides of said rolls, and spaced therefrom, about which the belt passes, and means normally supporting said pulley rolls releasably locked in fixed operative position with respect to the wringer mechanism during operation of the latter, said pulley rolls being mounted for manual upward movement out of operative position to permit access to the apron.

5. In a wringer mechanism including a frame, a pair of wringer rolls, a belt for feeding clothes to and from the wringer rolls, the upper run of said belt passing between said rolls, pulley rolls positioned on opposite sides of said wringer rolls, and spaced therefrom, about which said belt passes, arms supporting said pulley rolls and provided at their free ends with keyhole slots, headed studs, secured to the frame intermediate the pulley rolls and the wringer rolls, engageable in said keyhole slots to form a releasable pivotal connection between the arms and the frame, said slots being normally held in locking relation with the studs by the tension of the belt.

6. In a wringer mechanism, a frame including a bottom member and side members, wringer rolls journaled in the side members, said bottom member being inclined downwardly from its front and rear edges to a point beneath the wringer rolls, a drainage opening formed in the bottom member beneath the wringer rolls and a trough pivotally mounted in a fixed position relative to and beneath said bottom member to receive the drainage from said opening and discharge it selectively to the front or rear of the wringer mechanism.

7. In a wringer mechanism a feeding device which includes a perforated belt for feeding clothes to and from the bite of the wringer rolls, at least one pulley roll positioned to one side of the wringer rolls and spaced therefrom, about which the belt passes, a generally trough-shaped member positioned beneath the belt and adapted to receive water passing through the holes in the belt and conduct it to an opening formed in said member beneath the wringer rolls, said pulley roll being pivotally mounted to permit access to said member.

8. In a power driven wringer mechanism a feeding device which comprises a belt for feeding clothes to and from the bite of the wringer rolls, pivotally mounted guard members respectively overlying the feed and discharge portions of the belt, a plate pivoted to the wringer frame intermediate the inner ends of the guard members, means carried by said plate for transmitting power to the wringer rolls when the plate is in normal position, a cam formed on the edges of said plate adjacent the guard members, and means movable with each guard member and positioned to engage the adjacent cam when its associated guard member is raised to a predetermined height, to thereby swing said plate about its pivot and disrupt the transmission of power to the wringer rolls.
9. In a power driven wringer mechanism a feeding device which comprises a belt for feeding clothes to and from the bite of the wringer rolls, pivotally mounted guard members respectively overlying the feed and discharge portions of the belt, an electric circuit for supplying power to the wringer rolls, including a mercury switch, said switch being normally positioned to close said circuit, and means movable with each guard member to independently effect movement of said switch to circuit opening position when the associated guard member is raised to a predetermined height.
10. In a power driven wringer mechanism a feeding device which comprises a belt for feeding

clothes to and from the bite of the wringer rolls, pivotally mounted guard members respectively overlying the feed and discharge portions of the belt, an electric circuit, for supplying power to the wringer rolls, including a mercury switch pivotally mounted for movement to and from circuit closing position, a latch normally holding said switch in circuit closing position, means movable with each guard member to independently release said latch to permit movement of the switch to circuit opening position when the associated guard member is raised to a predetermined height and separate means for restoring said switch to latched position.

11. In a wringer mechanism including a pair of wringer rolls, a belt for feeding clothes to and from the wringer rolls, guard members positioned over the end portions of said belt and pivotally mounted for upward movement away from the belt, said guard members including knurled rolls normally engaging the clothes carried by the belt and means to drive said knurled rolls in the direction of the movement of the belt.

12. An attachment for a wringer provided with resilient rolls, comprising an apron projecting from each side of the wringer, rollers, means for hingedly and removably mounting said rollers on the ends of the apron and an endless belt trained over said rollers and traveling between said rolls.

30

HENRY L. MORIN.
